(57) CLAIM

The ornamental design for a container set, as shown and described.

DESCRIPTION

FIG. 1 is a top, front, perspective view of a container set showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and

FIG. 7 is a bottom view thereof.

FIG. 8 is a top front perspective view of a container set in use with additional environmental subject matter;

FIG. 9 is a front view thereof;

FIG. 10 is a rear view thereof;

FIG. 11 is a right side view thereof;

FIG. 12 is a left side view thereof;

FIG. 13 is a top view thereof; and

FIG. 14 is a bottom view thereof.

The features shown in broken lines are environmental subject matter to the container set and form no part of the claimed design. The features shown in long dash-short dash bolded broken lines in FIGS. 1-7 indicate the bounds of the claimed design and otherwise form no part of the claimed design.
